(57) **CLAIM**

The ornamental design for a container for cosmetic products, as shown and described.

DESCRIPTION

The file of this patent contains at least one drawing/photograph executed in color. Copies of this patent with color drawing(s)/photograph(s) will be provided by the Office upon request and payment of the necessary fee.

1. Container for cosmetic products

1.1 : Front

1.2 : Top

1.3 : Right

1.4 : Left

1.5 : Perspective

A back view and a bottom view are omitted as they are symmetrical to the front view and the top view respectively; light and shade expressed on the surface of the product in each view is a reflection of light.

1 Claim, 5 Drawing Sheets
